UNITED STATES PATENT OFFICE.

WILLIAM H. BLAKE, OF WATERBURY, CONNECTICUT.

DESIGN FOR SMOKING-PIPE CAP.

Specification forming part of Design No. 6,017, dated August 6, 1872.

To all whom it may concern:

Be it known that I, WILLIAM H. BLAKE, of Waterbury, county of New Haven, in the State of Connecticut, have originated and produced a new Design for Caps for Smoking-Pipes.

The nature of my design is fully represented in the accompanying drawing.

The lower part, which is to be secured to the bowl of the pipe, is provided with a border of crown-shaped points, as shown, a definite number not being requisite providing the proportions are kept to keep the symmetry of the same. The cap is provided with clasps, (four, more or less,) which serve to secure the cap to the base, said cap being rounded on the top and provided with a peak, as shown,

to which a ring may be attached or dispensed with. A chain connects the parts to prevent the loss of the cap.

I am aware of caps with scalloped borders and flanged rims on the top. These I do not claim; but

Having described my invention, I claim as new--

A design for a cap for a smoking-pipe, with an ornamental border and tip, substantially as shown and described.

WILLIAM H. BLAKE.
